AUTOMATIC FIRE EXTINGUISHING APPARATUS

John R. Hamilton, Cleveland Heights, Ohio, assignor to Automatic Sprinkler Company of America, Cleveland, Ohio, a corporation of Delaware

Application January 4, 1930. Serial No. 418,500

7 Claims. (Cl. 169—7)

This invention relates to mechanical fire extinguishing apparatus of the type disclosed in my prior Patent No. 1,264,394, granted April 30, 1918, in which a normally charged wet-pipe distributing system communicates with two different sources of supply of extinguishing fluid so arranged that the discharge of fluid from one source, known as the initial supply, initiates the discharge of fluid from the other source, known 10 as the main supply.

An object of this invention is to provide chemical mixing fire extinguishing apparatus of the type in which an impulse created by the discharge of an initial supply of fluid initiates the 15 discharge of the main supply of fluid, and having means for preventing the transfer of fluid through the impulse passage.

Another object of this invention is to provide, in fire extinguishing apparatus of this type, means 20 for feeding the initial supply of fluid at a substantially uniform hydrostatic pressure.

Still another object of this invention is to provide, in fire extinguishing equipment of the type referred to, an improved form of chemical mixing 25 apparatus.

A further object of this invention is to provide fire extinguishing apparatus in which means is employed in the distributing system to prevent air trapped in the system from retarding the 30 discharge of initial extinguishing fluid.

The invention may be further briefly summarized as consisting in certain novel combinations and arrangements of parts hereinafter described and particularly set out in the appended 35 claims.

In the accompanying sheets of drawings—

Fig. 1 is a side elevational view showing a fire extinguishing system embodying my invention;

Fig. 2 is an end elevational view of the same 40 system;

Fig. 3 is a sectional elevation taken on line 3—3 of Fig. 2;

Fig. 4 is a sectional elevation taken on line 4—4 of Fig. 2; and

Fig. 5 is a sectional plan view taken on line 5—5 of Fig. 2.

In the drawings, to which I shall now refer in detail, I have shown one fire extinguishing system embodying the principles of my invention, but it should be understood that the same principles may be embodied in various other systems and arrangements. The extinguishing system which I have illustrated is of the type in which a suction impulse created by the discharge of an initial supply of extinguishing fluid initiates

the discharge of extinguishing fluid from the main supply. In this system, as shown in Figs. 1 and 2, I provide the usual discharge piping 10 having suitably arranged sprinkler heads 11 thereon adapted to be fed with fire extinguishing agent from the riser 12. In the system illustrated the riser extends upwardly through the roof 13 and is connected to the horizontally disposed tank 14 supported upon the roof. This tank serves as an expansion chamber for the distributing system and, in addition, provides an initial supply of extinguishing fluid. The expansion tank, and the distributing system communicating therewith, are usually charged with a suitable non-freezing solution. The space above the level of the liquid in the expansion tank is normally maintained at atmospheric pressure by providing a restricted vent opening 15 through the wall of the tank.

At one end of the expansion tank I provide a suction chamber 16 which, in comparison with the expansion tank, is of relatively small volume. The interior of the suction chamber communicates with the expansion tank below the level of the liquid therein by means of the restricted passage 17 and with the space above the level of the liquid in the expansion tank by means of the restricted passage 18. The suction chamber is in open communication with the riser 12 through a passage 19 of relatively large size so that upon the opening of a sprinkler head this chamber will be quickly emptied creating a partial vacuum therein.

For the purpose of utilizing the impulse, created by the formation of the partial vacuum in the suction chamber, for initiating the supply of extinguishing agent to the riser 12 from the main supply contained in the mixing tank 20, I provide a diaphragm casing 21 mounted adjacent the suction chamber. A diaphragm 22 secured within the casing around its outer edge divides the interior of the casing into upper and lower chambers 23 and 24, respectively. The lower chamber 24 communicates with the suction chamber through the pipe 24', while the upper chamber 23 is connected to one end of the suction passage 25.

The chemical mixing tank 20 normally contains the main supply of extinguishing fluid, 105 which may be a quantity of soda solution, and is connected to the lower part of the riser 12. A check valve 26 is interposed between this lower part of the riser and the part thereof which is charged with the initial supply of extinguishing fluid. When pressure is created within the

tank 20 extinguishing fluid is forced upwardly through the check valve 26 into the riser 12.

For the purpose of creating pressure within the mixing tank 20 I provide a container 27 for storing and feeding a suitable chemical, such as sulphuric acid, into the soda solution contained within the mixing tank. The container 27 is housed within the casing or pressure dome 28 which is mounted on top of the tank 20 and 10 which is in open communication with the interior of the tank. As clearly shown in Fig. 3 of the drawings the container 27 comprises a cylindrical body portion 29 which stands loosely in, and is supported by, a cup-shaped member 30. The cup-shaped member forms the bottom wall of the container and is arranged with the skirt or side wall 31 thereof surrounding the side wall of the body portion. A horizontally extending wall 32 divides the container into two 20 acid storage chambers comprising an upper or primary storage chamber 33 and a lower or secondary storage chamber 34. Since the body portion is not attached to the cup-shaped member, acid will pass around the lower edge of the 25 wall of the body portion and rise in the annular space 34' to the level of the acid in the secondary storage chamber. The upper end of the annular space 34' is in open communication with the interior of the casing 28 so that pressure 30 within the tank 20 and within the casing 28 will be transmitted to the interior of the secondary acid storage chamber. In order that acid may be discharged from the secondary storage chamber, I provide a tubular member 35 which is arranged 35 in vertical position and secured in an opening through the bottom wall 33 so as to extend upwardly into the secondary acid storage chamber. An inverted cup-shaped member 37 is supported within the secondary chamber so as to surround 40 the upper end of the tubular member 35. The skirt of the member 37 extends downwardly into the acid contained in the chamber in spaced relation to the wall of the member 35 thus forming a siphon whereby acid may be discharged into the 45 mixing tank.

For discharging acid from the primary storage chamber into the mixing tank 20 I provide a tubular member 38 which is secured in an opening provided through the wall 32 so as to extend upwardly into the primary storage chamber and downwardly through the tubular member 35. An inverted cup-shaped member 39 surrounds the upper end of the tubular member 38 leaving an annular space between the walls of these members. The skirt of the cup-shaped member 39 extends below the level of the acid in the primary storage chamber, and, at a point adjacent the wall 32, openings 40 are provided through the skirt. When the level of the acid within the primary chamber is raised sufficiently acid will flow into the tubular member 38 and descend into the mixing chamber.

To facilitate the filling of the acid storage chambers I provide an overflow passage 41 which connects these chambers. This passage comprises a tubular member 42 having its lower end integral with the bottom wall of a well 43 provided in the wall 32. The opening of this tubular member communicates at its lower end with the interior of the secondary storage chamber, and its upper end communicates with the interior of the tubular member 44 which surrounds the tubular member 42. A wall 45 closes the upper end of the tubular member 44, while its side walls extend below the level of the acid in the primary storage

chamber and to a point adjacent the bottom wall of the well 43. When the acid storage chambers are to be filled acid is poured into the upper chamber 29. As the level of the acid rises in this chamber some of the acid enters the annular space between the tubular members 42 and 44. When the level of the acid reaches the opening at the upper end of the tubular member 42 it will overflow and pass downwardly through this tubular member into the secondary acid storage chamber. By providing the well 43 in the wall 32, the lower end of the tubular member 44 will always be sealed with liquid even though the amount of acid remaining in the primary chamber be very small. A restricted opening 46 is provided through the wall 45 so that pressures within casing 28 and within the secondary acid storage chamber are normally equalized.

When the system becomes operative pressure is generated within the mixing tank 20, by causing a starting charge of acid to be discharged from the primary storage chamber 33 into the mixing tank. For the purpose of causing the acid to be initially discharged from this primary storage chamber I provide a weight 47 which is adapted to be automatically released into this storage chamber. When released the weight descends into the acid raising the level of the liquid in the primary storage chamber and causing acid to be discharged through the tubular member 38 into the mixing tank 20. Suitable latch mechanism releasably supports the weight in an elevated position in the primary storage chamber with the lug 48 of the weight fulcrumed on the top wall of the tubular member 44. The weight itself is provided with a central opening which affords clearance for the cup-shaped member 39 when the weight descends into the storage chamber. Latch mechanism which I have found to be suitable for releasably supporting the weight comprises a bell-crank lever 49 pivotally mounted within the casing 28. The arm 50 of this lever is arranged to engage a projection 51 provided on the weight while the arm 52 is adapted to be engaged adjacent the end thereof by the head 53 of a pivoted rocker arm 54. The arm 52 is provided adjacent its free end with an opening 55 of sufficient size to accomodate the passage of the head 53 upon movement of the rocker arm to bring this head into registration with the opening. For pivotally mounting the rocker arm 54 within the wall of the casing 28, in such a manner as to prevent the escape of pressure from the casing, and to permit movement of the arm with very little friction, I provide a tubular sleeve 56 mounted in the wall of the casing. The opening through the sleeve is of sufficient size to permit the desired extent of rocking movement of the rocker arm 54. The rocker arm is pivotally mounted within the opening of the sleeve by supporting this member in a flexible body, such as a plug 57 formed of soft rubber or similar suitable material. This plug permits movement of the rocker arm with very little frictional resistance, and at the same time serves as a packing which prevents the loss of pressure through the opening of the sleeve.

The free end of the rocker arm 54 extends into a chamber 58 formed by securing the casing 59 to the casing 28. A diaphragm 60 is secured within the casing 59 so as to divide the space within this casing into the upper chamber 58 and a lower chamber 61. The suction passage 25 leading from the diaphragm casing 21 communicates with the chamber 61 so that suction

impulses occurring in this passage will be transmitted to this chamber. A stem 62 carried by the diaphragm 60 extends upwardly into the chamber 58 and is guided at its upper end by 5 a guide member 63 supported by the top wall of the casing. The free end of the rocker arm 54 extends through an opening provided in the stem 62, so that reciprocation of the stem caused by movement of the diaphragm will move the rocker 10 arm. A coil spring 64 mounted in the chamber 61 normally presses the diaphragm upwardly against the stop 65 provided on the inner surface of the wall of the casing. This spring normally holds the rocker arm with the head on the inner 15 end thereof in abutting relation with the arm 52 of the bell-crank 49.

The suction passage 25 and the chamber 61 are normally maintained at atmospheric pressure by providing a restricted opening 66 through 20 the member 67 mounted on the suction passage 25.

In the operation of the system, the fusing of a 25 sprinkler head permits the initial supply of extinguishing fluid contained in the distributing piping and in the suction chamber 18 to be discharged. The sudden discharge of fluid from the suction chamber causes a partial vacuum to be created within this chamber and within the chamber 24 of the diaphragm casing 21. This partial 30 vacuum causes a sudden downward movement of the diaphragm 22 causing a suction impulse to be transmitted through the passage 25 to the chamber 61. The suction impulse thus applied to the chamber 61 causes the diaphragm 60 to be moved 35 downwardly against the action of the coil spring 64, thus moving the rocker arm 54 about its pivot. The moving of the rocker arm about its pivot raises the head 53 on the inner end thereof allowing the opening 55 of the bell-crank arm 52 to move over the head. The arm 50 of the bell-crank moves simultaneously and releases the weight 47 which drops by gravity into the acid contained within the primary storage chamber 33 and causes a starting charge of acid to be discharged 40 into the mixing tank through the tubular member 38. Pressure is generated within the mixing tank 20 by the mixing of the acid with the soda solution and causes extinguishing fluid to be forced through the check valve 26 into the 45 riser 12 and out through the sprinkler heads. The pressure generated within the tank 20 enters the casing 28 and also enters the secondary acid storage chamber 34 through the restricted passage 43, the tubular member 35 and through the 50 annular space 34'. As fluid is discharged from the mixing tank 20, as a result of the pressure created therein by the action of the starting charge of acid, the pressure within the tank and within the casing 28 gradually decreases. This 55 decrease in pressure outside of the secondary acid storage chamber 34 permits the pressure trapped within this chamber to force acid out of the chamber through the tubular passage 35. The acid thus delivered into the mixing tank 20 through the passage 35 causes renewed chemical 60 action to generate pressure within the mixing tank. When the pressure within this tank again decreases, due to the discharge of fluid therefrom, additional acid will be forced from the secondary storage chamber and this continued process causes a substantially continuous supply of fluid to be delivered into the riser 12 from the mixing tank 20.

In the operation of systems of this type I have 75 found that when the system is initially charged

with extinguishing fluid air is trapped in the dead ends of the discharge piping. When the system becomes operative the air thus trapped in the discharge piping expands as the hydrostatic pressure in the suction chamber and in the riser is reduced. The expansion of this trapped air retards the emptying of the suction chamber and thus delays the formation of the suction impulse with the result that the pressure generating action of the chemical mixing means is also delayed. To prevent the trapping of air in the discharge piping, when the system is being initially charged, it has heretofore been necessary to provide vent piping cross connecting the ends of the discharge piping. This arrangement of piping is referred to in the art as a "grid" system of piping and is costly of installation. To overcome this difficulty without resorting to the use of a "grid" system, I provide check valves 68 in one or more of the connections 68' feeding the cross means 69 to prevent the expansion of the air thus trapped within the discharge piping. These check valves are arranged to permit extinguishing fluid to flow into the discharge piping from the riser 12 and to prevent a back-flow in the piping which is fed through the check valves.

In the fire extinguishing system which I have disclosed, it will be noted that the expansion tank 14 is arranged in a horizontal position and that the body of fluid contained therein has an extensive surface area. Because of this extensive surface area, any contraction or expansion of the fluid confined in the fluid distributing system will cause but slight change in the level of the fluid standing in the tank 14, and in the suction chamber 16 which is in communication therewith through the restricted passages 17 and 18. Therefore, since the level at which the fluid stands in the suction chamber is substantially constant at all times prior to the opening of a 103 sprinkler head, a hydrostatic head corresponding with that produced by a full distributing system, will be available at the sprinkler heads at the time of opening of the first sprinkler head. When the first sprinkler head opens, the fluid 108 standing in the system above that particular sprinkler head, and in the suction chamber 16, will begin to flow out of the system through the opened sprinkler head. During the first few moments after the opening of the initial sprinkler head, the level of the fluid in the suction chamber will drop rapidly, but before this chamber has been emptied, or at least before the fluid level has descended any material distance within the pipe 19, a suction impulse will be transmitted 113 through the pipe 25 to actuate the releasing mechanism, and the resulting pressure discharge of fluid from the main tank 20 will be started. In other words, the various parts of the apparatus are so designed and related that the chemical system is brought into operation before the suction chamber has been emptied, with the result that the discharge of fluid from the open 118 sprinkler head takes place at a substantially constant hydrostatic head and without any interruption or gap in its continuity.

The flexible diaphragms 22 and 60 and the flexible fulcrum plug or bushing 57 are important parts of my fire extinguishing system. The diaphragms readily permit suction impulses to be transmitted through the impulse passage but prevent any sustained flow of fluid through this passage. The flexible fulcrum plug prevents the escape of pressure fluid from the chemical container and at the same time permits the rocker 145

arm 54 to extend through the wall of this container so that it can be manipulated from the exterior of the container to release the discharge mechanism in the interior thereof.

5 While I have described the fire extinguishing system of my invention in a detailed manner, it should be understood, however, that I do not intend to limit myself to the precise arrangement shown and described but regard my invention as including such changes and modifications as do not involve a departure from the spirit of my invention and the scope of the appended claims.

Having thus described my invention, what I 15 claim is:

1. In chemical fire extinguishing apparatus, a chemical container for supplying chemical to a mixing tank containing a supply of extinguishing fluid, said chemical container comprising a fluid-tight casing in open communication with said tank, upper and lower chemical storage chambers in said casing each being arranged to discharge chemical into said mixing tank, one of said chambers being open to the pressure existing in said 20 casing, an overflow passage connecting said chambers, and means associated with said passage for retarding the equalization of pressure between said chambers.

2. In chemical fire extinguishing apparatus, a chemical container for supplying chemical to a mixing tank containing a supply of extinguishing fluid, said chemical container comprising a fluid-tight casing in open communication with said tank, upper and lower chemical storage 35 chambers in said casing each being arranged to discharge chemical into said mixing tank, one of said chambers being open to the pressure existing in said casing, and an overflow passage connecting said chambers, said passage having 40 an inlet opening below the normal level of chemical in the upper chamber and a restricted pressure equalizing opening above said normal level.

3. In fire extinguishing apparatus, the combination of a distributing system having a plurality of normally closed sprinkler heads adapted to be opened in response to fire conditions, a suction chamber disposed at an elevation above the uppermost of said sprinkler heads and having communication with said system at an elevation 45 above the uppermost sprinkler head, said system and said chamber being normally charged with an initial supply of extinguishing fluid, a mixing tank containing a main supply of extinguishing fluid, said distributing system being in communication with said mixing tank substantially at the bottom thereof, a chemical container having a passage for discharging chemical into said tank, said main supply of extinguishing fluid being chemically reactive with the chemical of 50 said container to generate gas pressure in said tank, a movable member for displacing chemical from said container into said passage, releasable means for supporting said movable member, said releasable means being responsive to a suction 55 impulse, and suction impulse transmitting means connecting said suction chamber and said releasable means.

4. In fire extinguishing apparatus, the combination of a distributing system having a plurality of normally closed sprinkler heads adapted to be opened in response to fire conditions, a suction chamber disposed above the elevation of the uppermost of said sprinkler heads and having communication with said system above the level 60 of the uppermost of said sprinkler heads, an

expansion tank disposed above the level of the uppermost of said sprinkler heads and having therein a body of fluid with an extensive horizontal surface area, said tank being in communication with said system through said chamber whereby fluid is normally maintained in the latter at substantially constant level as an initial supply to be fed to said system at a substantially uniform hydrostatic head during the first few moments after the opening of one of said sprinkler heads, a main supply tank of extinguishing fluid, said system having communication with said tank substantially at the bottom thereof, a container associated with said main supply tank for discharging chemical thereinto, said main supply of extinguishing fluid being chemically reactive with the chemical of said container for creating pressure in said tank for forcing fluid into said system, suction impulse responsive means for initiating the discharge of chemical into said tank, and means operably connecting said suction chamber with said suction impulse responsive means.

5. In fire extinguishing apparatus, the combination of a suction chamber adapted to contain an initial supply of extinguishing fluid, a distributing system comprising a riser, a plurality of sets of discharge pipes having sprinkler heads thereon which are normally closed but adapted to be opened in response to fire conditions, and cross-mains having connection with said riser for supplying fluid therefrom to the respective sets of discharge pipes, said suction chamber being disposed at an elevation above the uppermost of said sprinkler heads, and having communication with said riser at a point above the uppermost sprinkler head, a tank containing a main supply of extinguishing fluid and having communication substantially at the bottom thereof with said riser, a chemical container associated with said tank and having a passage for discharging chemical into the latter, said main supply of extinguishing fluid being chemically reactive with the chemical of said container, suction impulse responsive means for initiating the discharge of chemical into said tank, suction impulse transmitting means connecting said suction chamber with said suction impulse responsive means, and a check valve in each of said cross-mains, said check valve being arranged to permit a flow of extinguishing fluid into said discharge pipes from said riser but to prevent air trapped in one of the sets of said discharge pipes from expanding and interfering with the discharge of fluid from another of said sets of discharge pipes.

6. In fire extinguishing apparatus, the combination of a distributing system having a plurality of normally closed sprinkler heads adapted to be opened in response to fire conditions, a suction chamber disposed at an elevation above the uppermost of said sprinkler heads and having communication with said system at a point above the uppermost sprinkler head, said system and said chamber being normally charged with an initial supply of extinguishing fluid, a chemical mixing tank having communication near the bottom thereof with said system and containing a main supply of extinguishing fluid, a chemical container having a passage for discharging chemical into said mixing tank, said main supply of extinguishing fluid being chemically reactive with the chemical of said container for creating pressure in said mixing tank for forcing fluid into said system, a movable member for displacing chemical from said container into said

passage, releasable means for supporting said movable member including a movable arm extending through an opening in the wall of said chemical container, and resilient means sealing 5 said opening but permitting movement of said arm, said releasable means being responsive to a suction impulse, and suction impulse transmitting means connecting said suction chamber and said releasable means.

10 7. In fire extinguishing apparatus, the combination of a distributing system having a plurality of normally closed sprinkler heads adapted to be opened in response to fire conditions, a suction chamber disposed at an elevation above the 15 uppermost of said sprinkler heads and having communication with said system at a point above the uppermost sprinkler head, said system and said chamber being normally charged with an initial supply of extinguishing fluid, a chemical 20 mixing tank having communication adjacent the bottom thereof with said system and containing a main supply of extinguishing fluid, a chemical container having a passage for discharging chemical into said mixing tank, said main supply of extinguishing fluid being chemically reactive with the chemical of said container for creating a pressure in said tank for forcing fluid into said system, a movable member for displacing chemical from said container into said passage, releasable means for supporting said member including a rocker arm extending through and fulcrumed in an opening in the wall of said chemical container, and resilient means sealing said opening and permitting swinging movement of said arm, said releasable means being responsive to a suction impulse, and suction impulse transmitting means connecting said suction chamber and said releasable means.
